UNITED STATES PATENT OFFICE.

EUGENE E. MILES, OF AKRON, OHIO.

AIR GUN.

Application filed April 1, 1922. Serial No. 543,559.

To all whom it may concern:

Be it known that I, EUGENE E. MILES, a citizen of the United States, residing at Akron, in the county of Summit and State of Ohio, have invented a certain new and useful Improvement in Air Guns, of which the following is a full, clear, and exact description, reference being had to the accompanying drawings.

10 This invention relates to guns and has particular reference to an air gun or rifle in which the pellet is expelled by air pressure from a spring actuated plunger.

15 The primary object of the present invention is to provide an air gun in which the plunger shall be actuated by a compact form of multiple spring action which shall be capable of expelling the pellet with a higher muzzle velocity, greater accuracy, 20 and longer range, than is normally obtained with those guns employing a plunger actuated by a single spring.

25 Another object is to provide means for cushioning the plunger at the end of its compression stroke thereby to relieve the parts from dangerous impact and also to render the gun quiet in operation.

30 Another object is to provide a cocking and firing mechanism which shall be simple, compact and positive in operation and which shall be so constructed and arranged that the cocking lever will be normally retained against the gun stock, but which shall permit said lever to be easily moved a slight distance therefrom before the plunger springs are engaged, hence permitting the operator to fully grasp the gun stock while operating said lever to place the plunger springs under compression.

40 Another object is to provide a cocking and firing mechanism which shall be so constructed and arranged that the parts shall be securely retained in cocked position and thereby avoid accidental discharge of the 45 gun due to jarring or sudden shocks but which shall permit the gun to be easily fired by a slight pull on the trigger.

50 A still further object is to provide a gun of the aforesaid character which shall be simple in construction, highly efficient in operation and which shall be properly balanced and present a neat appearance.

55 With these and other objects in view, the invention consists in the various novel features of construction and arrangement or combination, all of which will be fully de-

scribed hereinafter and pointed out in the appended claims.

In the accompanying drawings wherein I have shown one form of my invention, Fig. 1 is a longitudinal sectional view through a gun constructed in accordance with my invention showing the parts in cocked position and ready to fire; Figs. 2 and 3 are similar views showing the parts in the discharged position and partly cocked position respectively; Fig. 4 is an enlarged detail sectional view showing the cocking and firing mechanism; Fig. 5 is a sectional view taken on the line 5—5 of Fig. 1; and Fig. 6 is an enlarged vertical sectional view through the plunger head and associated parts.

Describing by reference characters the various parts illustrated, 1 denotes the gun barrel which is secured by means of the threaded connection 2 to one end of a plunger cylinder indicated at 3. The opposite end of this cylinder is secured by means of the threaded connection 4 to a housing 5 enclosing the cocking and firing mechanism which will be fully described hereinafter. 6 denotes the stock which is secured to housing 5 by bolts 7 in the usual or any approved manner.

Slidably mounted within the cylinder 3 is a plunger 9, the head whereof is fitted with a sealing disk 10 formed from leather or other suitable material. The opposite end of the plunger head is provided with a threaded boss 11 which receives a longitudinally disposed tube 12. A plunger rod 14 is arranged within tube 12 and is threaded into the plunger head as indicated at 15. The opposite end of this rod is provided with a threaded portion 16 and a latch 17, threaded portion 16 having engaged therewith an internally threaded bushing 18 which is provided with a collar 19 which abuts the end of the tube 12. A coiled spring 20 is disposed about tube 12 and arranged between plunger head 9 and housing 5 and a second coiled spring 21 is disposed about rod 14 and arranged between boss 11 and a sleeve 22 slidably mounted on said rod. 105 Sleeve 22 is formed with a depending bifurcated projection 23 which is pivotally connected with one end of a cocking lever 25. A pair of links 26 are pivoted at one end to the cocking lever at 27 and at the other end said links are pivoted on a bolt 28 extending transversely through housing

5. This bolt also has pivotally mounted thereon a hammer 29 which is disposed between links 26. It will be noted in this connection that pivot point 27 is disposed 5 above a line connecting pivot 28 and the pivotal connection between the end of cocking lever 25 and projection 23, hence when the gun is in the cocked position as shown in Fig. 1, the pressure of spring 21 will normally retain the cocking lever against the gun stock. When the gun is in the discharged position as shown in Fig. 2 the lever may be easily moved a slight distance from the gun stock, as sleeve 22 may be moved rearwardly a slight distance before it abuts bushing 18. This permits the gun stock to be fully grasped at its smallest portion before the springs are placed under compression.

20. Pivots mounted between the links 26 is a cam lever 30 which engages with a stud 32 arranged transversely of housing 5. This lever is adapted to engage with a projection 33 formed on the hammer 29 to rotate said 25 hammer in a clockwise direction when the gun is cocked as will be more fully explained hereinafter. A second projection 34 is formed on hammer 29 and this projection is adapted to engage with a finger 35 formed 30 on a trigger 36 which is pivotally mounted in the lower portion of housing 5. A spring 37 interposed between said trigger and the housing normally urges finger 35 into engagement with the hammer.

35. A detent 40 is pivoted within housing 5, as indicated at 41, and is adapted to engage with latch 17 to retain the piston in retracted position, this being accomplished by a spring pressed pawl 42 engaging a 40 projection 43 on said detent. The hammer 29 is normally urged in a counter clockwise direction by a spring 45 (Figs. 1, 2, 3 and 5) which has one end thereof coiled about pivotal point 41 on one side of detent 40, 45 and then coiled in an opposite direction about pivotal point 28, whence said spring passes through the hammer and about pivotal points 28 and 41 on the opposite side of said hammer and detent.

50. The mechanism for cushioning the end of the plunger stroke after the gun is fired is shown in detail in Fig. 6. This mechanism comprises a spring pressed valve 47 which is slidably mounted in plunger head 9 in longitudinal alignment with the rifle bore. The valve is normally urged by spring 48 to a position slightly in advance of the sealing disk 10 and when the plunger moves forward in cylinder 3, the valve 47 55 will seal the inner end of the rifle bore thereby trapping a small volume of air in the cylinder which cushions the end of the plunger stroke and prevents serious impact with the gun barrel. It will be noted that 60 the peripheral edge of the inner end of the

gun barrel is beveled as indicated at 49 so that the slight impact of sealing disk 10 therewith will gradually form a feather edge 50 on the disk. This feather edge (which is exaggerated for purposes of illustration in the drawings) is effective in providing a tight seal with cylinder 3 during the discharge stroke of the plunger.

65. A loading plug 52 having a transverse bore 53 therethrough is rotatably mounted 70 in the gun barrel. This plug is provided with a handle 54 preferably extending in a direction parallel with bore 53, such handle facilitating rotation of the loading plug. The parts are so arranged that when the handle 54 is at right angles with the gun barrel, bore 53 will be in alignment with a vertical bore 55 formed in the top of the gun barrel and a pellet may be introduced 75 in the loading plug bore. Handle 54 is now 80 swung parallel with the gun barrel which places bore 53 and the pellet therein in alignment with the rifle bore.

85. Assuming that the gun is in the discharged position as shown in Fig. 2, the 90 operation will be as follows: Cocking lever 25 is pulled away from the gun stock to the position shown in Fig. 3. This serves to retract plunger 9 against the tension of spring 20. Also by virtue of the movement of links 26, the cam lever 30 rides over stud 32 and engages projection 33 on hammer 29 and rotates said hammer in a clockwise direction to a degree sufficient to permit finger 35 to engage projection 34 and 95 retain said hammer in retracted position against the tension of spring 45. Latch 17 on the end of the plunger rod will also engage an upstanding projection 60 on detent 40 and rotate said detent in a clockwise direction to a point where pawl 42 engages projection 43 on said detent to hold said detent against a counter clockwise rotation. As the cocking lever is moved back toward the stock, latch 17 will engage with detent 40 and retain the plunger in retracted position against the tension of spring 20. During the return movement of cocking lever 25, the sleeve 22 will slide forward on plunger rod 14 and compress spring 21. As the cocking lever approaches the gun stock, pivotal point 27 will rise above a line connecting pivotal point 28 and the inner pivoted end of the cocking lever, and hence the pressure of spring 21 will serve to retain the cocking lever against the gun stock, and contact of said lever against the stock will serve to retain spring 21 under compression.

100. A pellet is now introduced into the rifle bore as previously described and the gun, as 105 shown in Fig. 1, is ready to fire. This is accomplished by pulling trigger 36 which retracts finger 35 from its projection and permits hammer 29 to rotate in a counter clockwise direction under the influence of 110

spring 45. Hammer 29 strikes the upper end of pawl 42 and moves said pawl away from projection 43 on the detent 40. Plunger latch 17 exerting a strong pull on the detent

5 above the pivotal point 41 thereof causes said detent to rotate sufficiently to disengage the plunger rod and permit the plunger to move forward in cylinder 3 under the influence of springs 20 and 21. The air compressed in cylinder 3 forces the pellet through the rifle bore at high velocity. As the plunger approaches the gun barrel, it is cushioned as previously described.

Having thus described my invention, what

15 I claim is:

1. In a gun of the character set forth, the combination with a gun barrel, of an air compression cylinder operatively connected with said barrel, a piston in said cylinder, a

20 pair of independent springs for operating said piston, said springs being disposed one within the other, and means for placing each of said springs successively under compression.

25 2. In a gun of the character set forth, the combination with a gun barrel, of an air compression chamber operatively connected with said barrel, a piston in said chamber, a pair of independent springs 30 for operating said piston, and means for placing each of said springs successively under compression.

35 3. In a gun of the character set forth, the combination with a gun barrel, of a cocking and firing mechanism housing, an air compression cylinder arranged intermediate said barrel and housing, a piston in said cylinder, a rod connected to said piston, a spring interposed between said piston and said housing, a second spring interposed 40 between said piston and a movable abutment on said rod, and means for moving said abutment thereby to place said springs under compression.

45 4. In a gun of the character set forth, the combination with a gun barrel, of a cocking and firing mechanism housing, an air compression cylinder arranged between said barrel and housing, a piston in said cylinder, a pair of independent springs operatively connected with said piston, a cocking lever pivoted in said housing, and means connecting said lever and said springs whereby movement of said lever in one direction will compress one of said springs and movement in an opposite direction will compress the other of said springs.

50 5. In a gun of the character set forth, the combination with a gun barrel, of an air compression chamber operatively connected with said barrel, a piston in said chamber, means for operating said piston in said chamber, and a valve slidably mounted in said piston and adapted to seal said cham-

ber adjacent the end of the discharge stroke 65 of said piston thereby to cushion the impact between said piston and said gun barrel.

6. In a gun of the character set forth, the combination with a gun barrel, of an air compression chamber operatively connected with said barrel, a piston in said chamber, means for operating said piston in said cylinder, and a valve slidably mounted in said piston in alignment with the bore of said 70 gun barrel, said valve being yieldingly mounted in said piston and normally carried in advance thereof.

7. In a gun of the character set forth, the combination with a gun barrel, of an air compression chamber operatively connected with said barrel, a piston in said chamber, means for operating said piston in said cylinder, and a valve slidably and yieldingly mounted in said piston and adapted to seal 80 said gun barrel adjacent the end of the discharge stroke of said piston.

8. In a gun of the character set forth, the combination with a gun barrel, of an air compression chamber operatively connected with said barrel, a piston in said chamber, a relatively thick leather sealing disk carried by said piston and means associated with said gun barrel for forming and maintaining a relatively small feather edge on 90 said disk.

9. In a gun of the character set forth, the combination with a gun barrel, of an air compression chamber operatively connected with said barrel, a piston in said chamber, and a resilient sealing disk carried by said piston and adapted to contact with said gun barrel, the body portion of said disk being sufficiently thick to maintain substantially a constant diameter on the discharge stroke 100 of said piston, and said gun barrel having the peripheral edge of the inner end thereof beveled thereby to form a relatively small feather edge on said sealing disk.

10. In a gun of the character set forth, the combination with a gun barrel, of an air compression chamber operatively connected with said barrel, a piston in said chamber, a pair of springs for actuating said piston and a cocking lever operatively connected 110 to said springs and movable in opposite directions to compress said springs separately and successively.

11. In a gun of the character set forth, the combination with a gun barrel, of an air compression chamber operatively connected with said barrel, a piston in said chamber, a pair of springs for actuating said piston, a cocking lever operatively connected to said springs and movable in opposite directions to compress said springs separately and successively, and means connected to the lever to urge the same by the compres-

sion of the springs toward the housing and the gun stock when the lever is swung to cocked position.

12. In a gun of the character set forth, the combination with a gun barrel, of an air compression chamber operatively connected with said barrel, a piston in said chamber, a pair of springs for actuating said piston, a cocking lever operatively connected to 10 said springs and movable in opposite directions to compress said springs separately and successively, and means connected to the lever to urge the same by the compression of the springs toward the housing and the 15 gun stock when the lever is swung to cocked position, and to permit the lever to fall away from the housing and stock when the pressure of the springs is released by firing the gun.

20 13. In a gun of the character set forth, the combination with a gun barrel, of a cocking and firing mechanism housing, an air compression cylinder arranged between said barrel and housing, a piston in said cylinder, a 25 piston rod connected with said piston and having a latch operatively connected therewith and extending into said housing, a spring for actuating said piston in a given direction, a detent within said housing 30 adapted to engage said latch to retain said piston against the tension of said spring, a pawl for retaining said detent against rotation, a trigger, and means interposed between said trigger and pawl whereby movement 35 of the former will release said latch.

14. In a gun of the character set forth, the combination with a gun barrel, of a cocking and firing mechanism housing, an air compression cylinder arranged between said barrel and housing, a piston in said cylinder, a pair of independent springs operatively connected with said piston and adapted to urge 40 said piston in a given direction, a piston rod connected with said piston and having a latch operatively connected therewith, a detent adapted to engage said latch, a pawl for retaining said detent against rotation, a hammer adapted to contact with said pawl and release said detent, a trigger, and connections 45 between said trigger and hammer whereby movement of the former will cause said hammer to release said pawl.

15. In a gun of the character set forth, the combination with a gun barrel, of an air compression cylinder operatively connected 55 to said barrel, a piston in said cylinder, a piston rod connected with said piston, a spring for urging said piston in a given direction, a member slidably mounted on said piston rod and engaged with said spring, and a cocking lever operatively connected to 60 said member, the fulcrum of said lever being movable through the arc of a circle.

16. In a gun of the character set forth, the combination with a gun barrel, of an air compression cylinder operatively connected 65 to said barrel, a cocking and firing mechanism housing connected to said cylinder, a piston arranged within said cylinder and having a piston rod connected therewith and projecting into said housing, a pair of independent springs disposed about said piston rod, a member slidably on said piston rod and engaged with one of said springs and adapted to engage an abutment on said piston rod, a cocking lever operatively connected to said member, and a link pivoted adjacent one end within said housing and adjacent the opposite end to said lever, thereby to form a fulcrum for said lever, 80 said lever being adapted to move said piston against the tension of one of said springs when moved in one direction and place the other of said springs under compression when moved in an opposite direction.

17. In a gun of the character set forth, the combination with a gun barrel, of a cocking and firing mechanism housing, an air compression cylinder arranged intermediate 90 said barrel and housing, a piston in said cylinder, a rod connected to said piston, a spring interposed between said piston and said housing, a second spring interposed between 95 said piston and a movable abutment on said rod, and a cocking lever connected to said abutment and adapted to move said abutment in one direction to compress one of said springs and in an opposite direction to compress the other of said springs.

In testimony whereof, I hereunto affix my signature.

EUGENE E. MILES.
